UNITED STATES PATENT OFFICE.

JOHN F. O'CONNOR, OF CHICAGO, ILLINOIS, ASSIGNOR TO WILLIAM H. MINER, OF CHAZY, NEW YORK.

DOOR-OPERATING MECHANISM.

Application filed June 30, 1921. Serial No. 481,553.

To all whom it may concern:

Be it known that I, JOHN F. O'CONNOR, a citizen of the United States, residing at Chicago, in the county of Cook and State of Illinois, have invented a certain new and useful Improvement in Door-Operating Mechanisms, of which the following is a full, clear, concise, and exact description, reference being had to the accompanying drawings, forming a part of this specification.

This invention relates to improvements in door operating mechanisms.

In the operation of door mechanisms for dumping cars it is highly desirable to provide a certain amount of lost motion between the part directly engaged by the operating tools such as the claw bar and the main shaft proper of the door mechanism, during the opening movements of the doors in order to eliminate possible injury to the operators. Heretofore, where no such lost motion safety devices have been employed, frequent injury to the operators has occurred due to the load on the doors causing the shaft to rotate at high speed and thereby wrenching the operating tool from the hands of the operator and causing the tool to strike and injure the operator.

The object of my invention is to provide a simple and relatively inexpensive and compact safety device involving any desired amount of lost motion between the part of the mechanism directly actuated by the operating tool and the shaft proper of the mechanism.

In the drawing forming a part of this specification, Fig. 1 is an elevational view of the end of the door operating mechanism such as found on a dump car and wherein 40 is embodied my invention. Fig. 2 is a vertical sectional view taken substantially on the line 2—2 of Fig. 1. Fig. 3 is a vertical sectional view taken substantially on the line 3—3 of Fig. 2.

In said drawing, 13 denotes a portion of an operating shaft of a door mechanism which may be of any well known form and the exact details of which I consider unnecessary to describe in connection with my 50 invention. Preferably the door mechanism proper will be of that type wherein the linkages are self-locked when the doors are in closed position and where it is required to rotate the door shaft through a short arc 55 in order to release the linkages before the

load on the doors is free to swing the latter at high speed under the influence of the load thereon, such as shown in the Campbell Patent 1,342,095, dated June 1, 1920.

In carrying out my invention, I employ 60 what may be termed a clutch or lost motion device which comprises, broadly, an outer clutch member A; an inner clutch member B; a gear C; and a plurality of pinions or spur gears D—D.

The clutch member B is formed with a hub 11 having a recess of square or other non-circular formation 12 adapted to fit over the correspondingly shaped end of the shaft 13 of the door operating mechanism proper. 70 The clutch member B is permanently and rigidly secured to said shaft 13 by any suitable means such as the rivet 14.

In addition to the hub 11 the clutch member B is provided with an annular flange 75 15, from the periphery of which extend a series of radially disposed teeth 16 cooperative with a pivoted locking dog 17 in a well-known manner to lock the mechanism when the doors are in closed position.

Applied to the annular flange 15 is a cover plate or cap 18, the two parts being rigidly secured as by rivets 19—19. By means of the cap 18 and flange 15, a combined housing and bearing is formed for 80 the inner member of the clutch A and the other parts of the mechanism as will be apparent from an inspection of Fig. 2.

The gear C is preferably made integral 90 with the clutch member B and is located in axial alinement with the shaft 13. In actual practice, there will preferably be 12 teeth on said gear C.

The clutch member A is the one directly 95 operated by the claw bar or other tool usually used in unloading cars. For this purpose the member A is provided with an outwardly projecting squared section 20 and adapted to receive the claw bar. At the inner end of the squared section 20, the clutch member A is formed with a circular flange 21 fitting inside of the cap 18 as best shown in Fig. 2. Integrally formed with said flange 21 and extending inwardly therefrom are, in the embodiment shown in the 105 drawing, three studs 22—22 uniformly spaced with respect to the axis of the shaft 13.

Mounted on each stud 22 and freely rotatable thereon is a pinion D, the teeth of 110

the pinion D meshing with the gear C as clearly shown in Fig. 3. Each pinion D, on the side adjacent the flange 21, is formed with an incomplete annular groove or recess 24 which extends through an arc of slightly less than 360° and leaving a shoulder or web 25. Extending within each of said grooves 24 is a cylindrical pin or post 26 preferably formed integrally with the flange 21 of the 10 clutch member A. When the gear C is provided with 12 teeth, each pinion D will preferably have 18 teeth so as to obtain the necessary amount of lost motion between the clutch members A and B as about to be described.

In Figure 1 of the drawing, the parts are shown in the position assumed after the doors have been closed. To unwind or release the door operating mechanism and thus open the doors, the operation is as follows: The operator first applies the claw bar or other suitable tool to the squared section 20 of the clutch member A and rotates the latter in a counter-clockwise direction a 25 slight amount and sufficient to permit disengagement of the locking dog 17. The operator then turns the clutch member A in a clockwise direction and at this point it will be understood that the door operating 30 mechanism is in self-locked condition so that the shaft 13 and gear C carried thereby will remain stationary until some direct turning force is applied to the shaft 13. As the operator continues the rotation of the clutch member A in a clockwise direction, the pinions D will travel bodily around the gear C and also, due to the planetary gearing arrangement illustrated, the pinions D will be given a relatively slow individual 35 rotation in a clockwise direction about each of their respective studs 22. This action will continue until the pinions D have been rotated in a clockwise direction about their individual axes sufficient to bring the stop webs 25 against the opposite sides of the pins 26. As will be understood by those skilled in the art, this amount of lost motion may be varied as desired by changing the length of the annular groove 24 and the 40 ratio of the teeth of the gear C to the teeth of the pinions D. At the end of the action just described and when the stop webs 25 come into engagement with the pins 26, the pinions D are then locked against any 45 further rotation about their individual axes and consequently, continued rotation of the clutch member A in a clockwise direction will produce rotation of the gear C and the shaft 13 in a clockwise direction. This latter action is continued 50 until the shaft 13 has been rotated sufficiently to cause release or unlocking of the door operating mechanism proper and, therefore, the shaft 13 will be rotated under 55 the load on the doors. During the running

or turning of the shaft 13 under the door loads, the operator is free to hold the clutch member A stationary since the rotation of the gear C in a clockwise direction will produce a counter-clockwise rotation of each of the pinions D about their individual axes. Slightly less than a complete revolution of each pinion D is permitted on account of the length of the annular slot 24 as hereinbefore described and in view of the fact that there 60 are only twelve teeth on the gear C more than a complete free rotation of the gear C and shaft 13 is allowed with respect to the clutch member A until the condition is restored as shown in Fig. 3.

80 I have herein shown and described what I now consider the preferred manner of carrying out the invention, but the same is merely illustrative and I contemplate all changes and modifications that come within the scope of the claims appended hereto.

I claim:

1. In a safety device for door operating mechanisms, the combination with two relatively rotatable clutch members, one of which is adapted to be manually operated and the other of which is adapted to rotate always simultaneously with a shaft of the mechanism; of a gear rigid with one of said clutch members; a pinion in mesh with said gear, said pinion being rotatable about a stub shaft axially arranged with reference thereto and carried by the other of said clutch members; and cooperable means on said pinion and the member by which it is carried arranged to limit the rotation of said pinion with respect to the clutch member carrying it to less than a complete revolution about its individual axis.

2. In a safety device for door operating mechanisms, the combination with two relatively rotatable clutch members, one of which is adapted to be manually operated and the other of which is adapted to rotate always simultaneously with a shaft of the mechanism; of a gear rigid with one of said clutch members; a plurality of pinions uniformly spaced around said gear and in mesh therewith, each of said pinions being rotatably mounted about an individual axis 110 on the other of said clutch members; and cooperable means on each pinion and the clutch member by which they are carried arranged to limit the rotation of the pinions about their individual axes with respect to the 115 clutch member carrying them, to less than a complete revolution.

3. In a safety device for door operating mechanisms, the combination with a tool operated clutch member; of a second clutch member adapted to be rigidly secured to a shaft of the mechanism; a gear rigid with said second named clutch member; a pinion rotatably mounted about an individual axis 125 on said tool operated clutch member, said 130

pinion being provided with peripheral external teeth meshing with said gear; and cooperating means on said pinion and the tool operated clutch member arranged to limit 5 the rotation of said pinion with respect to the tool operated clutch member to less than a complete revolution about its individual axis.

4. In a safety device for door operating mechanisms, the combination with a tool operated clutch member; of a second clutch member adapted to be rigidly secured to a shaft of the mechanism; a gear rigid with 10 said second named clutch member; a plurality of pinions uniformly spaced around 15 said gear and in mesh therewith, each of said pinions being rotatably mounted about an individual axis on said tool operated clutch member; and cooperable means on said tool 20 operated clutch member and each of the pinions arranged to limit the rotation of each pinion about its individual axis to less than a complete revolution.

5. In a safety device for door operating mechanisms, the combination with a clutch 25 member adapted to be rigidly secured to a

shaft of the mechanism, said member having an annular flange; of a cap plate secured to said annular flange and forming therewith a housing; peripheral teeth carried by 30 said clutch member; a tool operated clutch member rotatably mounted within said housing; a gear within said housing rigid with said first named clutch member and located centrally thereof; a plurality of bearing studs carried by said tool operated clutch member and disposed uniformly around said gear; a pinion loosely rotatably mounted on each of said bearing studs, said pinions being in mesh with said gear, each 40 pinion having an incomplete annular groove on the side thereof adjacent the tool operated clutch member; and a pin rigid with said clutch member extending into each of 45 said grooves.

In witness that I claim the foregoing I have hereunto subscribed my name this 23rd day of June 1921.

JOHN F. O'CONNOR.
